M. LEVY
AUTOMATIC AND MANUALLY OPERATED
FIRE ALARM SIGNAL STATION
Filed Nov. 16, 1951

INVENTOR.
Morris Levy
BY
W.W. Williamson
ATTORNEY

Applicant claims that the invention relates to an automatic and manually operated fire alarm signal station, and particularly to an apparatus for automatically operating a switch in an electric alarm circuit, said switch including two contactors, one of which is normally maintained in an open position by means to be displaced by manual operation for closing the circuit and the other contactor being closed by the action of abnormal or excessive heat in the vicinity of the apparatus.

An object of this invention is to produce a fire alarm signal station which will operate automatically under the action of heat and which can be operated manually by a person discovering a fire in a building equipped with the apparatus, for the purpose of warning occupants of the building of probable danger.

Another object of the invention is to produce a fire alarm signal station comprising a switch in an electric alarm circuit, said switch including two contactors, one of which is normally retained in an open position by means to be displaced by manual operation for closing the circuit and the other contactor being closed by the action of abnormal or excessive heat in the vicinity of the station.

Another object of this invention is to produce an apparatus of the kind described in which one contactor is normally maintained in an open position by a fragile panel that can be broken by a manually operated instrument to allow said contactor to close, and the other of said contactors being closed by the action of excessive heat in proximity to the apparatus.

A further object of the invention is to produce a fire alarm signal station of the type mentioned wherein one contactor of the switch is normally maintained in an open position by manually dislocatable means which, when the restraint is removed, is caused to close by spring action, and the other contactor including heat responsive means to cause said other contactor to close.

A still further object of the present invention is to produce a fire alarm station including the customary spring contactor switch in combination with a thermostatically actuated secondary contactor responsive to abnormal or excessive heat for closing said switch.

With the above and other objects in view this invention consists of the details of construction and combination of elements hereinafter set forth and then designated by the claim.

In order that those skilled in the art to which this invention appertains may understand how to make and use the same I will describe its construction in detail, referring by numerals to the accompanying drawing forming a part hereof, in which:

Fig. 1 is a front face view of a signal station constructed according to this invention with

55

the various parts labeled by numerals corresponding to the numerals used in the claims, and showing the front face of the housing 10, the chamber 11, the stationary contact member 16, the anchor plate 18, the contactor 20, the spring 21, the nut 21, the loop 22, the elbow 23, the seat 12, the panel 13, the screws 14, the cavity 15, the contact 17, and the cavity 15.

Fig. 2 is an enlarged fragmentary section on the line 2-2 of Fig. 1.

Fig. 3 is also an enlarged fragmentary broken section on the line 3-3 of Fig. 1 with the heat responsive element shown in the normally open position and illustrating it in closed position in dotted lines.

Fig. 4 is a section on the line 4-4 of Fig. 1 on the same scale as said Fig. 1.

2

portions broken out to illustrate details of construction.

Fig. 2 is an enlarged fragmentary section on the line 2-2 of Fig. 1.

Fig. 3 is also an enlarged fragmentary broken section on the line 3-3 of Fig. 1 with the heat responsive element shown in the normally open position and illustrating it in closed position in dotted lines.

Fig. 4 is a section on the line 4-4 of Fig. 1 on the same scale as said Fig. 1.

For the purpose of illustrating the invention I have shown a support, housing or body 10 having a chamber 11 formed in the front face thereof so that the front end of said chamber is open to the exterior of the housing. The open end of said chamber is surrounded by a recessed seat 12 for the fragile panel 13, such as glass, said panel being detachably held in place by appropriate securing means, such as screws 14, attached to the housing with portions overlapping the edges of the panel 13.

In the bottom of the chamber 11 is formed a cavity 15 which is bridged at one end by a stationary contact member 16, preferably in the form of a plate of good electric conductivity, fixedly held in place by screws 17 projected through the back of the housing and threaded into the stationary contact member 16. A conductor representing one side of an electric alarm system is adapted to be attached to one of said screws for electric connection with the stationary contact 16 as one pole of the switch to be presently described.

On the bottom of the chamber 11 is mounted an anchor plate 18, which constitutes the other pole of the switch, said plate being secured in place by suitable fastening means, such as screws 19 projected through the back of the housing and threaded into said anchor plate 18. A conductor representing the other side of the electric alarm system is adapted to be attached to one of said screws for electric connection with the anchor plate 18 as the other pole of the switch.

The anchor plate 18 is located to one side of the cavity 15 adjacent the end opposite the position of the stationary contact member 16 and to one of the screws 19 is attached the fixed end of the spring contactor 20 by a nut 21, Fig. 1.

The contactor 20 may be formed from strong spring wire having the fixed end attached to the anchor plate by one of the screws 19 and the nut 21 and is fashioned to provide a U-shaped loop 22. One of the branches of said loop is bent outward and then inward to form an elbow 23,

UNITED STATES PATENT OFFICE

2,652,468

AUTOMATIC AND MANUALLY OPERATED FIRE ALARM SIGNAL STATION

Morris Levy, Philadelphia, Pa.

Application November 16, 1951, Serial No. 256,770

1 Claim. (Cl. 200—138)

1

My invention relates to new and useful automatic and manually operated fire alarm signal stations such as are placed on the interior walls of buildings to warn the occupants, in particular, and outsiders, in general, when a fire occurs.

An object of this invention is to produce a fire alarm signal station which will operate automatically under the action of heat and which can be operated manually by a person discovering a fire in a building equipped with the apparatus, for the purpose of warning occupants of the building of probable danger.

Another object of the invention is to produce a fire alarm signal station comprising a switch in an electric alarm circuit, said switch including two contactors, one of which is normally retained in an open position by means to be displaced by manual operation for closing the circuit and the other contactor being closed by the action of abnormal or excessive heat in the vicinity of the station.

Another object of this invention is to produce an apparatus of the kind described in which one contactor is normally maintained in an open position by a fragile panel that can be broken by a manually operated instrument to allow said contactor to close, and the other of said contactors being closed by the action of excessive heat in proximity to the apparatus.

A further object of the invention is to produce a fire alarm signal station of the type mentioned wherein one contactor of the switch is normally maintained in an open position by manually dislocatable means which, when the restraint is removed, is caused to close by spring action, and the other contactor including heat responsive means to cause said other contactor to close.

A still further object of the present invention is to produce a fire alarm station including the customary spring contactor switch in combination with a thermostatically actuated secondary contactor responsive to abnormal or excessive heat for closing said switch.

With the above and other objects in view this invention consists of the details of construction and combination of elements hereinafter set forth and then designated by the claim.

In order that those skilled in the art to which this invention appertains may understand how to make and use the same I will describe its construction in detail, referring by numerals to the accompanying drawing forming a part hereof, in which:

Fig. 1 is a front face view of a signal station constructed according to this invention with

55

Fig. 4, the legs of which diverge, and finally the end of the wire is bent to produce the contact terminal 24. This contact terminal 24 is positioned within the cavity 15 in back of the stationary contact member 16. Said cavity 15 is of sufficient depth to allow a limited oscillatory movement of the contact terminal 24 of the spring contactor 20 whereby said terminal 24 may be moved out of engagement with the stationary contact member 16 under certain conditions. For example, the elbow 23 is of such dimensions that when the contact terminal 24 of the spring contactor is in engagement with the under side of the stationary contact member 16 said elbow 23 projects outside of the plane of the seat 12. Therefore, when the elbow is in or inside of the plane of the seat, as when retracted by the panel 13 resting on said seat 12, the contact terminal 24 will be out of engagement with the stationary contact member 16.

The stationary contact member 16, the anchor plate 18, the screws for said member and plate, and the spring contactor constitute a switch which is retained in an open condition by a manually dislocatable switch restraining means. For purposes of illustration, the restraining means comprises the fragile panel 13 which engages the elbow portion 23 and retracts the spring contactor when said panel is seated and secured in place. When the restraining means is dislocated, as when the fragile panel is broken or removed, the spring contactor 20 will be released and the switch will close to produce an alarm.

The foregoing is a description of a simple form of fire alarm signal station as disclosed in my Patent No. 2,545,854, dated March 21, 1951, and included as a part of my Patent No. 2,570,823, dated October 9, 1951.

In the housing is also a compartment 25 which is closed except for a multiplicity of holes 26 leading thereto from the exterior of said housing and the opening forming the communication of said compartment with the chamber 11. In this compartment 25 is mounted the heat responsive means 27 for also closing the alarm circuit.

The heat responsive means herein shown comprises a frame 28 located in the compartment 25 with a shaft 29 journaled in ears 30 of said frame, said shaft being sufficient in length to cause the inner end thereof to project into the chamber 11. On said inner end of the shaft 29 is a secondary contact 31 normally out of engagement with the stationary contact 16, as shown in elevation in Fig. 3, but capable of engaging said stationary contact under certain conditions, as shown by dotted lines in said Fig. 3, for closing the switch 20 between the stationary contact 16 and the anchor plate 18, constituting opposite poles of said switch, through said secondary contact and the elements of the heat responsive means which is electrically bonded to the anchor plate 18, as by a wire 32.

To the outer end of the shaft 29 is attached one end of a coiled thermostatic element 33, within the vented end of the compartment 25, while the other end of said element is held in a fixed position by attachment to a projection 34 extending from an adjacent ear of the frame 28. When the thermostatic element 33 expands under the influence of heat it has a tendency to unwind thus imparting a rotary movement to the shaft 29 in the direction to cause the secondary contact 31 to move towards and finally engage the stationary contact or pole piece 16 for closing the switch and thereby completing the alarm circuit.

15 The foregoing description of a heat responsive device for closing the switch is illustrative only and used for the purpose of explaining the nature of my invention and is intended to cover any type of thermostatic element as an equivalent of that set forth.

20 Of course I do not wish to be limited to the exact details of construction herein shown and described as these may be varied within the scope of the appended claim without departing from the spirit of my invention.

25 Having described my invention what I claim as new and useful is:

An automatic and manually operated fire alarm station, comprising a housing with a chamber 30 therein open at the front, a panel seat surrounding said open front, a fragile panel mounted on the seat with means to hold it in place, a stationary contact and an anchoring means secured within the chamber and constituting the poles 35 of a switch structure, a resiliently operated primary movable contact member fixed to one pole and in cooperative relation to the other pole, said primary movable contact member being held out of contact with said other pole by the fragile 40 panel which when broken releases said primary contact member to complete a circuit for producing a continuous alarm, and a second contact member responsive to heat and electrically connected to the first mentioned pole and normally 45 out of engagement with said other pole and engaging said other pole when said second contact member is subjected to abnormal heat to also complete the same circuit for also producing a continuous alarm.

50 MORRIS LEVY.
